COLLAPSIBLE TRUNK

Fred Leichtfuss, New York, N. Y.

Application March 20, 1936, Serial No. 69,797

1 Claim. (Cl. 217—59)

The main object of this invention is to provide a trunk which is completely collapsible, so that when not in use for storing, may be concealed in a small and convenient space.

5 The above and other objects will become apparent in the description below in which characters of reference refer to like-named parts in the drawing.

Referring briefly to the drawing, Figure 1 is 10 a top plan view of the collapsible trunk showing the same in extended position with the cover in cross section.

Figure 2 is a side elevational view of the collapsible trunk with the cover in raised position.

15 Figure 3 is a cross sectional view taken on line 3—3 of Figure 2.

Figure 4 is a side elevational view of the collapsible trunk showing the same in partly collapsed position.

20 Referring in detail to the drawing the numeral 10, indicates the bottom of the trunk. The front edge of the bottom has a bar member 11, attached thereto permanently and the rear edge also is provided with a bar 12, which rises to a

25 slightly greater height than the bar 11. On the inside edges of these bars 11 and 12, hinge members 13, are provided. The hinge on bar 11, is connected to the front collapsible wall 14, while the rear bar 12, also provided with a hinge has a rear wall 15 having depressions 15' in its upper edge (Fig. 3), attached thereto. End walls 16 and 17, are secured to the bottom in collapsible condition by hinge members 18. The rear wall 15, has a U-shaped loop 19, secured thereto. This

30 pair of loop members 19, engage straps 20, which are secured to the cover panel 21, at spaced apart positions on the underside of the panel. The panel is bounded on the front and end sides by a rim 22, which snugly fits around the three complemental sides of the trunk when in extended position. The strips 20, hold or retain the cover in position so that it can be slid rearward and rotated simultaneously. The end walls and front and rear wall of the collapsible trunk

45 are retained in upright position by hook and eye members 23, which are arranged at the corners of the upright walls and when the trunk is in position for storing, a tray 24, may be mounted on the hook and eye members. A lock 50 may be provided on the cover rim 22, with a cooperating member on the front wall 14, to secure the trunk in locked position when in use.

In assembling the trunk for use, the end walls 16 and 17, are placed in upright position after the front wall 14, and rear wall 15, have been

similarly moved. When these walls are in upright position the hooks and eyelet members 23, are secured thus retaining the trunk in extended position. The straps 20, cooperating with members 19, permit the rotation and the sliding of the cover panel at any position along the length of the straps, while the depressions 15' in the upper edge of the rear wall provide for a smooth turning of the cover when the same is either lifted for guidance over the top of the 10 walls forming the trunk, or lowered into its position parallel to the rear wall of the trunk when the same is to be opened. In collapsing the trunk member the end walls 16 and 17, are first turned inwardly about the hinges 18, and then 15 the front cover 14, is turned about the hinge 13, to lie flat on the end bases 16 and 17, after which the rear wall 15, is similarly turned over about its hinge and the cover panel then rests upon the wall section 15. 20

It is to be noted that certain changes in form and construction may be made without departing from the spirit and scope of the invention.

I claim:

In a collapsible trunk having a bottom, end walls and a front wall and rear wall having depressions in its upper edge, and foldable upon said bottom and a sliding cover, hooks attached to the inner faces of the endwalls and eyes attached to the inner faces of the front wall and rear wall adapted to be engaged by said hooks to keep the walls rigid in their unfolded position to constitute a trunk, said eyes at the front and rear walls of the trunk projecting into the same and hooks at the end walls of the trunk projecting into the same, forming a support for a removable tray, loops attached to the outer face of the rear wall and projecting above depressions formed in the upper edge of said rear wall, and parallel, comparatively wide metal strips secured at their ends to the inner face of the cover and slidably guided through said loops, said strips having inwardly bent portions near their outer ends into which the loops engage when the cover is in its open position depending parallel to the outer face of the rear wall, said inwardly bent strip portion in conjunction with the depressions in the upper edge of the rear wall forming a swivel permitting a smoothly turning of the cover when the same is lifted for guidance over the tops of the walls to act as trunk cover, handles on the end walls, and a lock for locking the cover to the front wall. 50
